CLAIM

The ornamental design for a substrate for spectroscopic analysis, as shown and described.

DESCRIPTION

1. Substrate for spectroscopic analysis

1.1 : Perspective

1.2 : Front

1.3 : Back

1.4 : Top

1.5 : Bottom

1.6 : Left

1.7 : Right

1.8 : SECTIONAL VIEW

1.9 : SECTIONAL VIEW

1.10 : REFERENCE VIEW SHOWING THE STATE IN USE
